UNITED STATES PATENT OFFICE.

GEORGE W. PINE, OF TROY, NEW YORK.

BOSOM-SHIRT.

SPECIFICATION forming part of Letters Patent No. 313,520, dated March 10, 1885.

Application filed May 27, 1884. (Model.)

To all whom it may concern:

Be it known that I, GEORGE W. PINE, of the city of Troy, county of Rensselaer, State of New York, have invented a new and useful Improvement in Bosom-Shirts, of which the following is a specification.

My invention relates to bosom-shirts and the attachment of the bosom to the shirt by means of a bias-cut border-piece that is folded centrally and longitudinally and laid with its cut edges parallel to the edges of the bosom, sewed thereto, turned over and down on the line of union, with the outer edge of the folded border-piece attached to the shirt at the front, and a like border-piece attached to the bosom-lining or body side facing in the same manner as that attached to the bosom proper, and said lining border-piece on its folded edge sewed to the inner surface of the shirt opposite to the bosom at the front and to and through the exteriorly-connected edge of the border-piece of the bosom proper, the object and purpose of my invention being to unite a rounded bosom in a shirt-front without gathers in the piece by which it is connected to the shirt, or gathers in the latter.

Accompanying this specification, to form a part of it, there are three plates of drawings containing five figures illustrating my invention, with the same designation of its parts by letter-reference used in all of them.

Of these illustrations, Figure 1 shows the position of the parts after a bias-cut border-strip was folded longitudinally and centrally, laid with its cut edges coincident to those of the bosom-lining and sewed thereto, then turned over and down on the line of its union, with the fold edge of said border sewed to the inside surface of the shirt-front, and inside the line of which union of border and shirt-body the latter was subsequently cut out to produce the bosom-opening. Fig. 2 shows a section taken on the line $x'x'$ of Fig. 1. Fig. 3 shows the previously-connected bosom, bosom-ply, and border-piece as sewed to the edge of the bosom-opening and to and through the border-piece of the lining on the inner body side of the shirt, the parts at the neck-opening and on one side thereof being shown as detached and turned over and down to better indicate their relative position. Fig. 4 shows a shirt-front with the attachment of the bosom completed. Fig.

5 is a section taken on the line x^2x^2 of Fig. 4.

All the sections show the thicknesses of the parts as exaggerated, to better illustrate them. 55

The several parts of the attachment constituting my invention are designated by letter-reference, and the process steps by which the parts are connected are described as follows:

The letter A indicates the shirt-front, which 60 may be made with or without a re-enforce. When used with the latter, it and the shirt are together connected to the other parts, as the shirt-front would be if used alone.

The letter B designates the bosom; P, the 65 bosom-ply; F, the body side facing or lining of the bosom; O', the border of the bosom proper, and O² the border of the lining F.

The letter d' indicates the outer surface of the shirt-front, and d² its body side surface. 70

The parts thus designated are attached as follows: Both the border-pieces O' and O² are 75 cut on a bias line of the fabric, and they are each folded centrally and longitudinally. The border-piece O² is laid with its cut edges par-

allel with that of the bosom-lining, sewed as thus placed, turned over and down, so as to bring its central fold to the outer edge, the stitching connecting the border and lining being 80 designated at a'. The border-piece O' is attached at a² to the edges of the bosom proper and bosom-ply in the same manner as the border O² is attached to the bosom-lining. After

the borders have thus separately been attached the bosom-lining and connected border on the 85 outer folded edge of the latter, as indicated at s, are attached to the body side of the shirt-front opposite to where the bosom comes at the front, and when this union has been made the shirt-body, where inside of this union with 90

the said border, may be cut out to form the bosom-opening G, with the parts appearing as at Fig. 1. After the bosom-opening has 95

been thus cut out, then the outer edge of the border-piece on the bosom proper is sewed at a² to and through the exterior of the shirt-front at the edge of the bosom-opening, (when said opening is made,) or to and through the outer edge of the border-piece on the bosom-lining previously connected to the body side 100 of the shirt-front, with the parts appearing as illustrated at Figs. 3, 4, and 5.

While I have shown and described the bosom-lining, by means of its border-piece, as

attached to the inner surface of the shirt-front before the bosom-opening is cut out, if desired, the bosom, by means of its border-piece, may be attached to the shirt before the opening is 5 cut out, and the lining subsequently attached; or, if desired, the shirt-front, where included by the bosom proper and lining, may remain intact to form a thickness of the ply. In either instance the combined attachment of the 10 bosom proper and bosom-lining by means of a bias cut and folded border-piece would be the same.

Having thus described my invention, what I 15 claim, and desire to secure by Letters Patent, is—

1. In combination with the shirt and the attached bosom thereof, the folded border-strip O², attached to the inner side of the shirt, and the folded border-strip O', attached to the

outer side of the shirt and to the inner side of 20 the bosom, substantially as described, and for the purpose set forth.

2. In combination with the shirt, the shirt-bosom, and the inside lining, F, the folded border-strip O², interposed and secured be- 25 tween the lining F and the inner side of the shirt, and the border-strip O', secured to the outer face of the shirt and to the inner side of the bosom, substantially as described, and for the purpose set forth.

Signed at Troy, New York, this 8th day of May, 1884, in the presence of the two witnesses whose names were by them hereto written.

GEORGE W. PINE.
